UNITED STATES PATENT OFFICE.

ERNEST E. BENNETT, OF OAKHURST, NEW JERSEY.

FOLDING SQUARE.

No. 927,096.

Specification of Letters Patent.

Patented July 6, 1909.

Application filed July 2, 1908. Serial No. 441,708.

To all whom it may concern:

Be it known that I, ERNEST E. BENNETT, a citizen of the United States, residing at Oakhurst, in the county of Monmouth and State 5 of New Jersey, have invented a new and useful Improvement in Folding Squares, of which the following is a specification.

This invention relates to a folding square and the object of the invention is a device of 10 this kind which can be set and locked in a number of positions and which when not in use can be folded into a smaller space than the rigid square in ordinary use.

The invention consists in the novel features of construction hereinafter described, 15 pointed out in the claims and shown in the accompanying drawings, in which—

Figure 1 is a plan view of my square, adjusted positions being indicated by dotted 20 lines. Fig. 2 is a section on the line 2—2 of Fig. 1. Fig. 3 is a detail plan view, a supporting plate being removed. Fig. 4 is a section on the line 4—4 of Fig. 3.

In these drawings 1 represents the stationary side of the square which is provided adjacent one end with notches 2 and 3, said notches having different inclinations, and adjacent its end this side member is provided with a socket 4. To this end portion of the 25 square and at right angles to the said side member 1 are riveted supporting plates 5 spaced apart and which carry adjacent their outer ends a transversely arranged pin 6. The second member 7 of the square is longitudinally slotted as shown at 8 and works 30 between the supporting plates 5, the pin 6 passing loosely through the slot 8. An inner end of the member 7 is inclined to a wedge shaped point 9, this inclined or pointed end 35 resting within the socket 4 when the device is used as a square and the wedge shaped point 9 fitting in either the notch 2 or the notch 3 when the member 7 is to be locked 40 in one of its other positions. I prefer to 45 thread one end of the pin 6 and to cut out one of the plates 5 and insert in said cut out portion an ordinary nut 10 into which the pin threads, and the other end of the pin is provided with a round slotted head 11 said

head being beveled so that a slight turn of 50 the pin will draw the parts closely together. By means of this construction if the threads become worn it is only necessary to insert a new standard nut in place of the worn one, which can be done at a trifling cost, the said 55 nut acting as a threaded bushing. It will be obvious that the member 7 can be locked at right angles to the member 1 by dropping it into the socket 4, or at other angles by wedging the point 9 into the notches, and it 60 will also be obvious that these notches may be so formed as to give the inclination desired, and in practice they would comprise those angles most usually called for in the 65 class of work for which that particular form of the invention was designed. For example the device may be sold with the member 7 adapted to be locked in position to give a square, two sides of a pentagon and two sides of an octagon. 70

What I claim is:—

1. A device of the kind described comprising a stationary member of a square, supporting plates carried by said square at one end, a threaded pin passing through said 75 plates, a movable member pivotally mounted upon said pin and having a reduced wedge shaped inner end, notches being cut in the stationary member to receive said point, and a socket being formed in said stationary 80 member to receive the inner end of the movable member when at right angles to the stationary member.

2. A device of the kind described comprising a square formed of two disconnected 85 members, plates carried by one of said members and spaced apart, and a locking pin carried by said plates and serving as a pivot point for the other member, the member carrying the plates being notched, and the pivoted member having a wedge shaped inner 90 end adapted to engage said notches, as and for the purpose set forth.

ERNEST E. BENNETT.
